UNITED STATES PATENT OFFICE.

ADOLPH G. CARLSON, OF CHICAGO, ILLINOIS, ASSIGNOR OF ONE-HALF
TO FRED H. FITCH, OF CHICAGO, ILLINOIS.

POCKET-RECORDER FOR EXPENSE ACCOUNTS.

No. 800,205.

Specification of Letters Patent.

Patented Sept. 26, 1905.

Application filed September 22, 1904. Serial No. 225,434.

To all whom it may concern:

Be it known that I, ADOLPH G. CARLSON, a citizen of the United States, residing at Chicago, in the county of Cook and State of Illinois, have invented a new and useful Pocket Recorder for Expense Accounts, of which the following is a specification.

This invention relates to pocket-recorders for expense accounts.

10 The object of the invention is to provide a pocket-recorder for expense or other accounts of traveling men or the like and which is simple in construction and efficient in operation.

15 The invention consists substantially in the construction, combination, location, and arrangement of parts, all as will be more fully hereinafter set forth, as shown in the accompanying drawings, and finally pointed out in the appended claims.

20 Referring to the accompanying drawings and to the various views and reference-signs appearing thereon, Figure 1 is a view in front elevation of a register or recording device embodying the principles of my invention. Fig.

25 2 is a view in section on the line 2 2, Fig. 3, looking in the direction of the arrows. Fig. 3 is a view in transverse section on the line 3 3, Fig. 1, looking in the direction of the arrows. Fig. 4 is a view in section on the

30 line 4 4, Fig. 3, looking in the direction of the arrows. Fig. 5 is a detached detail view of the type wheel or disk employed in the construction and operation of my invention. Fig.

35 6 is a view similar to Fig. 5, showing a record-disk. Fig. 7 is a view similar to Fig. 6, upon a reduced scale, showing a modified form of carbon or ink-ribbon employed in the operation of my invention.

40 In keeping a record of expense or other accounts by traveling salesmen or the like it is exceedingly convenient to have a register or recording device capable of being carried in the pocket and whereon may be registered and recorded not only the amounts expended, 45 but also the purposes for which the expenditures are made—that is, it is frequently desirable to keep a record of the items of the expense account. It frequently happens that a traveling salesman or other person keeping 50 an expense account dislikes when in the presence of others to be seen entering items of expense on his expense account.

It is among the special purposes of my present invention to provide a construction of

register or recorder mechanism which is simple and efficient, wherein an expense account may be kept and itemized and without exposing the user to jest or ridicule of companions, and wherein a record is made of the items and of the amounts expended therefor. It is to 55 be understood that these objects may be accomplished in many specifically different ways and by many specifically different constructions and arrangements of parts. While, therefore, I have shown and will now describe 60 one form of construction embodying the principles of my invention and the best form in which I at present contemplate carrying my invention into practical operation, I desire it to be understood that my invention is not to 70 be limited or restricted to the exact details of construction and arrangement herein set forth.

In carrying out my invention I propose to provide an inclosing casing, (designated by 75 reference-sign A,) which may be in the form of an ordinary watch-case provided with a transparent face B, as in the form of a watch-crystal, and a hinged cover C, after the fashion of an open-faced watch, the hinged cover 80 C being pivoted to the case in any simple or convenient manner, as indicated at D, Fig. 3. Within the casing I arrange a supporting-plate E, having a central opening therethrough, forming a bearing for a hub F of a 85 printing wheel or disk G, said hub extending through and journaled in the opening in the supporting-plate E. Mounted upon the projecting end of hub F to revolve therewith is a pointer H. Also mounted upon hub F to 90 rotate therewith is a pinion J, with which meshes a pinion or other form of gear-wheel K, through which rotation is imparted to the type or printing disk G. The printing or type disk G is designed to carry suitable type 95 or other printing devices, and in practice, although I do not desire to be limited or restricted thereto, I propose to arrange the type L upon the side surface of the type wheel or disk and preferably in rows spirally arranged. The number and character of the type will 100 be dependent upon the amount designed to be registered or recorded upon the device. For instance, if the device is to be used for recording dollars and cents up to ninety-nine dollars 105 and ninety-nine cents then each group or spiral row of type will include four figures. For instance, one spiral group or row will include

four 0's, another spiral group or row will include four 1's, another row four 2's, and so on, up to 9. If the register is designed for amounts of nine dollars and ninety-nine cents 5 or under, then each spiral row or group will contain three type, and if nine hundred and ninety-nine dollars and ninety-nine cents are to be recorded then each spiral row will include five type. Where it is desired to also 10 register or record an itemized expense account indicating the purpose for which each expenditure of the account has been made the various items of the account may be indicated in any convenient manner—as, for instance, 15 by letters or combinations of letters. The type for these letters may be arranged on the type wheel or disk G in any convenient manner. In practice and as shown I propose to employ, say, two type-letters in connection 20 with each spiral row or group of type. Thus in the form shown the spiral row or group of 0's has associated therewith the letters "S" and "T," the spiral row or group of numerals "1" has associated therewith the letters 25 "A" and "B," and so on, these letters being arranged to conform to the spiral character of the rows or groups of type. The pointer H, which is mounted upon to rotate with the hub of the type disk or wheel G, is associated with 30 a dial-plate M, which, if desired and as shown, may be mounted upon the outer face or surface of supporting-plate E. This dial-plate I propose to provide with graduations, marks, letters, and numerals corresponding with the 35 type carried upon the inner face of the type wheel or disk G. Thus, as shown in Fig. 1, the pointer H has been actuated to point to one of the numerals "8," disclosed through the transparent dial B. When the pointer is 40 in this position, the corresponding type "8" on the inner face of the type disk or wheel G is brought into proper position to print or form a record therefrom, and when the pointer H is shifted or moved, as will presently be 45 more fully explained, into register with any of the figures or letters of the dial M the type-wheel is simultaneously shifted or moved into position to bring the corresponding type of the inner face thereof into printing or recording position. The pointer H and type disk or wheel are rotated to the desired positions through the gears J and K, with the latter of which meshes a bevel-gear N, carried upon a sleeved stem O, arranged to extend 50 through the casing A, and upon which is mounted a bur or thumb portion P, by which 55 said bevel-gear N may be actuated.

I propose to print the amounts registered so as to record the same and so as to make 60 and retain a record of the various items and amounts registered on the device. To this end I propose to employ a record-sheet, which may be of any suitable or desired form. In one form shown the record-sheet R (see Fig. 65 6) is in the form of a disk, and I arrange the

same to be suitably supported within the casing so that the printing wheel or disk may be successively rotated or moved rotatively to bring any desired letter or figure into printing position relatively thereto, so as to print 70 thereon the desired amount and also the character for indicating the object or purpose of the expenditure, and I propose to so mount the record sheet or disk that when one item and the amount thereof has been printed said 75 sheet or disk may be shifted into position to receive the next item and amount. In order to accomplish these results and to efficiently clamp and hold the record strip or sheet and also to indicate the amount of the record disk 80 or sheet which has been used so that the person operating the device may see at a glance just how much of the record sheet or disk has been used up, I employ two disks A' B', (see Fig. 3,) and I mount the disk A' upon a 85 pin or stud C', arranged to extend through the hub F' and upon the extended end of which is mounted a pointer D', arranged to coöperate with a circular series of graduations upon the dial M. The record sheet or 90 disk R is centrally perforated, as indicated at E', Fig. 6, to receive therethrough the inner end of stud C', and said record sheet or disk is designed to be clamped and held between the disks A' B', preferably with a corresponding sheet or disk F' of carbon-paper, 95 ink-ribbon, or other similar inking device, said carbon or ribbon sheet or disk lying next to the face or surface of the printing-wheel carrying the printing characters. The disk 100 B' is provided with an extended hub G', which is received within a barrel H', carried by the cover C of the casing, said disk being clamped or held in any convenient manner—as, for instance, by means of a rod or bolt J', so coupled or connected to the hub G' as to permit slight relative movement of disk B' toward 105 and from disk A' when these disks are brought together. A spring K', arranged to engage the end of hub G', serves to normally but 110 yieldingly press the disk B' toward and into clamping relation with respect to disk A' to efficiently clamp and hold the record strip or disk R and carbon-paper or ink-ribbon F' therebetween. If desired and in order to 115 more efficiently hold the record sheet or disk and the carbon or ink ribbon as well as to insure simultaneous rotative movement of disks A' B', pins (indicated at L') carried by disk B' are arranged to project through the carbon and record sheets and into disk A'. 120

In Fig. 7 I have shown a modified form of carbon or ink strip or disk M', which is in the form of a ring carried by a central stiffening-disk N', through which a central opening P' is formed to receive the inner end of stud C'. It is believed that such a construction will be 125 efficient where an ink-ribbon is employed in place of a carbon disk, the central portion N' forming a stiffening for the ring M' of ink- 130

ribbon material to efficiently hold the same in ring shape.

After an entry has been printed on the record-sheet, as above indicated, the record-sheet is shifted so as to bring the same into proper position to receive the next entry. This shifting of the record-sheet may be effected in many different ways. I have shown a simple arrangement for accomplishing the result, to which, however, I do not desire to be limited or restricted, in which provision is made of means for shifting the record-sheet rotarily and wherein a ratchet-wheel R' is mounted upon the hub G' of disk B' to rotate therewith. Coöperating with ratchet-wheel R' is a pawl S' , spring-pressed into engagement with the ratchet-teeth of wheel R' —as, for instance, by means of a spring T' . (See Fig. 2.) The pawl S' is pivotally mounted upon a sliding rod A^2 , mounted to slide in guides $B^2 C^2$, suitably mounted within the case A , and a spring D^2 serves to yieldingly maintain rod A^2 in one limit of its movement. The free end of this rod is arranged to project into proximity to a plate or disk E^2 , carried upon a rod F^2 , (see Fig. 3,) arranged to extend longitudinally through sleeve O and having its outer end connected to a thumb-piece G^2 , arranged to be telescoped over or upon a hub H^2 of bur, or thumb-piece P , as clearly shown. A spring J^2 , interposed between bur P and thumb-piece G^2 , serves to normally but yieldingly maintain thumb-piece G^2 in raised position above bur P . By depressing thumb-piece G^2 against the action of spring J^2 rod F^2 is projected downwardly, carrying disk or plate E^2 downwardly to engage the end of rod A^2 , thereby projecting the latter against the action of spring D^2 and in a direction to cause pawl S' to move ratchet-wheel R' rotarily through any desired distance—say, for instance, through the distance corresponding to one ratchet-tooth thereon. The rotative movement thus imparted to ratchet-disk R' imparts a rotative movement to disks $B' A'$ and a step of rotary displacement to the record-sheet and also a step of movement to pointer D' , thereby not only presenting a fresh space or surface of the record-strip to receive the next entry to be recorded or printed thereon, but also through pointer D' and the graduations associated therewith indicating the extent or amount of rotary displacement of the record strip or sheet.

The printing may be effected in many different ways. I have shown a simple construction and arrangement for accomplishing the desired result wherein a printing-platen K^2 is carried upon the free end of a spring-yoke L^2 , suitably secured upon the inner face of the cover C . The printing-platen K^2 is arranged opposite a convenient point of the side surface of the printing-disk which carries the printing characters L and in position for the record sheet or strip R , and the car-

bon-sheet or ink-ribbon F' or M' , as the case may be, to pass between the platen K^2 and the surface of the printing-disk which carries the printing characters, as clearly shown in Fig. 3, and the printing operation is effected by deflecting the spring-yoke L^2 , which carries the printing-platen against the spring action of the yoke, and then releasing the same, thereby delivering something in the nature of a hammer-blow upon the record-sheet and against the particular printing character lying opposite the platen K^2 at the time of delivery of such blow. The platen K^2 , or rather the spring-yoke L^2 , supporting the same, may be deflected and released to accomplish the printing operation, or the delivery of the hammer-blow above referred to may be accomplished in many different ways. For instance, in the form shown, to which my invention is not to be limited or restricted, the rod F^2 , carrying disk or plate E^2 , is mounted for rotary movement, being connected for this purpose to the thumb-piece G^2 , which is rotatively mounted upon the hub portion H^2 of bur P , and on the under face of plate E^2 is arranged a cam M^2 , designed, when said plate E^2 is rotated, to engage the free end of yoke L^2 and deflect or bend the same back against the spring action thereof until the point of the cam passes beyond the projecting end of the yoke L^2 , thereby releasing said yoke and permitting the spring action thereof to effect the hammer-blow of the platen and the consequent recording of the printing character lying opposite thereto at the time such blow is delivered.

If desired and in order to indicate to the user of the device that the printing operation has been effected, a spring-pawl N^2 may be provided and arranged for a shoulder O^2 upon the free end thereof to engage a notch in the periphery of disk E^2 , the engagement of shoulder O^2 in such notch resulting in a clicking noise as well as imposing a retarding effect upon the rotative movement of disk E^2 , thereby informing the user that the printing operation has been effected and the hammer-blow delivered by the printing-platen K^2 .

If desired and in order to insure the proper centering of the printing-disk G with reference to the point of application of the hammer-blow by the printing-platen K^2 , the periphery of the printing-disk G is provided with a series of notches P^2 , corresponding in number and relation to the various printing characters mounted upon the side face thereof, and a spring-pawl (indicated in dotted lines at R^2 , Fig. 1) coöperates with the notches P^2 , thereby centering or insuring the proper position of the several printing characters when brought opposite the point of application of the printing-platen K^2 .

It is believed that the operation of the device will be readily understood from the foregoing description, but may be briefly stated

as follows, assuming that the printing wheel or disk and the means for rotatively displacing the same occupy the relative positions thereof, as shown in Fig. 3. The case-cover 5 C is opened and a record disk or sheet R and a coöperating carbon disk or sheet or ink-ribbon or the like is placed upon the inner end of stud C' and against disk A'. The cover C is then closed, thereby carrying the disk B' 10 into clamping relation against the disk A', thereby clamping the carbon or ink disk and the record disk or sheet therebetween and locking said disks A' B' to rotatively move together, the spring K' securing a spring-clamping action of disk B' against disk A' to efficiently clamp therebetween the carbon or ribbon and the record disks or sheets. Now suppose it is desired to register the amount 15 of a hotel bill and that the letter "H" is used to designate the hotel bill. The bur P is rotatively moved thereby through gears N, K, and J, imparting rotative movement to the type or printing disk G and pointer H until the latter is brought opposite the letter "H" 20 on the face of the dial-plate. This operation will bring the type character "H" on the printing-disk opposite the point of application of the printing-platen K². The thumb-piece G² is now rotated, thereby causing cam M² to 25 engage the free end of spring-yoke L², upon which printing-platen K² is carried, and to deflect said spring-yoke until the cam releases the same, thereby permitting the spring action of said yoke to carry the printing-platen 30 with a hammer-blow against the printing character "H" with the carbon or ink ribbon and record sheets or disks therebetween, and hence effecting a record of the type character "H" on the record-sheet. Now suppose the 35 hotel bill amounts to twenty-five dollars and forty cents. The bur P is again rotated until the pointer H registers with the outermost "2" of the group or spiral row of numerals "2" of the dial-plate. This action will bring 40 the type character "2" on the face of the printing-disk opposite the printing-platen K², and then the latter is actuated, as above explained, to effect a printing of the "2" on the record strip or sheet. The bur P is next actuated 45 to bring the pointer H opposite the numeral "5," corresponding to units denomination in the group or spiral row of the numeral "5" on the dial-plate, thereby correspondingly actuating the printing-disk G to bring the corresponding type character "5" 50 opposite the printing-platen, when the above operation of effecting a printing of the same on the record strip or sheet is repeated. The dial-pointer H is again moved to register with the "4" in the group or row containing the numerals "4" of the disk-plate corresponding to the tenths denomination, when the printing operation above described is again 55 repeated. The pointer H is now actuated to be brought into register with the "0" of the 60

"0" group on the dial-plate of hundredths denomination, thereby correspondingly bringing the type character opposite the printing-platen, and the printing operation is then repeated, thus completing the register "H 25.40" 70 on the record-sheet, and hence indicating thereon that the user has spent twenty-five dollars and forty cents for his hotel bill. The completion of this record necessitates the shifting of the record sheet or strip to bring 75 a fresh surface into printing relation with respect to the platen and the type wheel or disk. To accomplish this result, the thumb-piece G² is depressed, thereby causing the under surface of plate E² to impinge against the end of rod A², thereby projecting said rod longitudinally to enable the pawl S' thereon to rotatively move ratchet-wheel R', and hence imparting rotative movement for one step to disks B' A' and to pointer D', thus not only 80 bringing a fresh space of the record-strip into printing relation, but also indicating on the face of the dial-plate that the printing strip or disk has been rotatively actuated and the extent of such actuation. Now suppose 85 the user desires to register the expenditure of ten cents for cigars. By employing the letters "CG" to designate cigars and suitably manipulating the device, as above described, the item and the amount will be printed 90 upon the record sheet or disk in the same manner as above described.

As above indicated, the printing characters L upon the face of the printing wheel or disk are arranged in groups, the members of each 100 group being arranged in a spiral row, thereby enabling any member of any group to be brought into printing relation without affecting the printing of any other member of such group when the printing operation is accomplished, and these printing characters, numerals, and letters may be sufficient in number to permit of the printing of any desired denomination or of the use of any desired letter-key to designate the items of expenditure, 105 as will be evident and readily understood.

If desired, and in order to prevent retrograde movement of ratchet-disk R' and the parts affected by the rotative movement thereof, a spring-actuated pawl R² may be employed in association with ratchet-disk R' (see Fig. 2) to lock or hold the same against reverse movement when actuated by its actuating-pawl S'.

The printing-platen and its supporting 120 yoke may be guided in the movements thereof when actuated to deliver the printing-blow in any convenient manner—as, for instance, by a guide-plate S². This printing-platen, its supporting-yoke, and the clamping-disk D' being 125 all mounted on the cover C of the case, it will be seen that by opening the case-cover the record strip or sheet may be removed and replaced when filled and the carbon sheet or strip or ink-ribbon renewed with facility.

A recording device embodying the construction above referred to is simple and compact, and being constructed in the form of a watch may be readily carried in the pocket and used for the purposes for which it is intended with facility and in such manner as to avoid the user being humiliated in the keeping of an expense-account. It will also be seen that the expense-account is kept accurately, and a record is made thereof, which may be retained and which itemizes the expenditures.

Having now set forth the object and nature of my invention and a construction embodying the principles thereof, what I claim as new and useful and of my own invention, and desire to secure by Letters Patent, is—

1. A pocket recording device for expense-accounts, comprising a casing, a printing-wheel arranged therein and carrying type characters on the side face thereof, a record-sheet support also arranged within said casing and adjacent to the side face of the type-wheel, a spring-supported platen, means for successively positioning said printing-wheel, and means for actuating said platen to deliver a hammer-blow upon the record-sheet to press the same into printing contact with the positioned characters on the side face of the printing-wheel.
2. A recording device for expense-accounts, comprising a casing, a printing-wheel journaled for axial rotation therein and carrying type characters on the face thereof, and means for rotatively moving said wheel to bring any desired type character on the face thereof into printing position, in combination with a record-sheet support arranged concentric with the axis of rotative movement of the printing-wheel and adjacent the side surface thereof, a movable printing-platen, and means for operating the same to deliver a hammer-blow upon the record-sheet for taking an impression thereon from the positioned type characters on the printing-wheel.
3. A pocket recording device for expense-accounts, comprising a casing, a printing-wheel journaled therein for axial rotation and carrying type characters on the side face thereof, a stationary dial-plate, a pointer connected to revolve with said type-wheel and co-operating with the dial-plate, a record-sheet supported within the casing and in concentric relation with respect to the axis of rotation of the printing-wheel and arranged adjacent the printing-face of said type-wheel, a spring-supported printing-platen, and means for actuating said platen to deliver a hammer-blow upon the record-sheet for printing from the type upon the type-wheel.
4. A pocket recording device for expense-accounts, comprising a casing, a type-wheel mounted therein for axial rotative movement and having type characters arranged in groups upon the side face thereof, a pointer mounted to rotate with said type-wheel, a dial-plate

having characters corresponding in grouping arrangement to the type upon the face of said type-wheel and with which said pointer co-operates, a record-sheet support mounted concentric with the axis of rotative movement of the printing-wheel and arranged adjacent to the printing side face of said wheel, and means for pressing the record-sheet into printing relation with respect to the printing characters carried on the face of the type-wheel.

5. A pocket recording device for expense-accounts, including a casing, a type-wheel journaled for rotative movement within said casing and carrying type characters arranged in groups, the members of each group of characters being arranged in staggered relation, a pointer connected to rotate with said type-wheel, a dial-plate with which said pointer co-operates, said dial-plate bearing characters arranged in groups in staggered relation to correspond with the groups of type upon the type-wheel, a record-sheet support, means for printing from the type characters upon said record-sheet support, and means for displacing said record-sheet.

6. A pocket recording device for expense-accounts, including a casing, a type-wheel mounted therein for rotative movement and carrying type characters upon the side face thereof, a record-sheet support mounted within the casing and adjacent the type-carrying side face of said type-wheel and adapted to support a record-sheet, a spring-mounted printing-platen, and means for operating said platen to effect a printing from the type of the type-wheel upon the record-sheet.

7. A pocket recording device for expense-accounts, including a casing, a printing-wheel journaled therein for axial rotative movement and provided with type characters upon the side face thereof, a record-sheet support mounted concentric with the axis of rotation of said printing-wheel and adjacent said printing-wheel, a movable platen to press the record-sheet into printing contact with the type upon said printing-wheel, means for rotatively moving said printing-wheel to position the printing-type thereon, means for rotatively displacing said record-sheet support, and for operating the printing-platen.

8. A pocket recording device for expense or other accounts, including a casing, a type-wheel journaled for rotative movement within said casing, a record-sheet support, means for supporting the same within said casing and with the record-sheet in proximity to the type-wheel, a spring-mounted yoke independent of the record-sheet support, a platen carried thereby, the record-sheet being arranged between said platen and the type-wheel, and means for actuating said platen to press the recording-sheet into printing contact with the type on said printing-wheel.

9. A pocket recording device for expense or other accounts, including a casing, a print-

ing-wheel carrying type and mounted for axial rotative movement within the casing, a support for a record-sheet mounted for rotative movement upon an axis concentric with the printing-wheel and arranged adjacent thereto, means for successively positioning the printing-wheel to bring the desired type into printing relation with respect to the record-sheet, means for rotatively displacing said record-sheet support, and for pressing the record-sheet into printing contact with the positioned type on the type-wheel.

10. A pocket recording device for expense or other accounts, including a casing, a printing-wheel journaled for rotative movement within the casing and carrying type characters, means for rotatively displacing said type-wheel to position the type thereon for printing, a record-sheet support arranged within the casing and adjacent the type-wheel, means for displacing said record-sheet support relative to the type-wheel, a spring-supported platen, and a cam for actuating said platen to deliver a hammer-blow upon the record-sheet to effect a printing thereon from the type on the type-wheel.

11. A pocket recording device for expense or other accounts, including a casing, a printing-wheel journaled therein for rotative movement and carrying type characters, a record-sheet support arranged within the casing to hold a record-sheet adjacent the path of type characters upon said printing-wheel, means for rotatively actuating said printing-wheel to bring the desired type character successively into printing position with respect to the record-sheet, means for rotatively displacing the record-sheet support, a movable platen, said last-mentioned means actuating the platen to press the record-sheet into printing contact with said characters.

12. A pocket recording device for expense or other accounts, including a casing having a hinged cover, a printing-wheel journaled for rotative movement within said casing, means for supporting a record-sheet adjacent said wheel, a spring-mounted printing-platen supported upon the hinged cover of said casing, and means also carried by said hinged cover for clamping said record-sheet.

13. A pocket recording device for expense or other accounts, including a casing, a printing-wheel journaled therein for rotative movement and carrying printing characters, means for rotatively actuating said printing-wheel, means for centering said wheel in adjusted position, a record-sheet support arranged adjacent the printing-wheel, means for moving said support relatively to the printing-wheel, and a printing-platen independent of said support, said moving means actuating the platen to press the record-sheet into printing relation with respect to the type-wheel.

14. A pocket recording device for expense or other accounts, including a casing, a print-

ing-wheel journaled therein for rotative movement and carrying printing-characters, means for clamping and supporting a record-sheet within said casing, means for successively positioning the type-wheel, means for rotatively shifting the record-sheet, a printing-platen independent of said clamping and supporting means, and means for actuating said platen to carry the record-sheet into printing relation with respect to the type upon the printing-wheel.

15. A pocket recording device for expense or other accounts, including a casing, a printing-wheel mounted therein for rotative movement, a pointer mounted to rotate with said wheel, a dial-plate with which said pointer cooperates, a supporting-clamp for a record-sheet also rotatively mounted within said casing, a pointer connected to rotate with said supporting-clamp, means for rotatively adjusting said printing-wheel, means for pressing the record-sheet into printing contact with the type upon said wheel, and means for rotatively displacing said supporting-clamp.

16. A pocket recording device for expense or other accounts, including a casing, a supporting-plate mounted therein, a printing-wheel having a hub arranged to project through said supporting-plate for rotative movement in the bearing afforded thereby, a pointer mounted upon the extended hub of said wheel, type characters carried by said wheel, a pin extending through the hub of said wheel, a clamp-plate mounted on said pin, a pointer also mounted on said pin, a cooperating clamp-plate to clamp a record-sheet against said first-mentioned clamp-plate, a ratchet mounted upon the last-mentioned clamp-plate, means for operating said ratchet-wheel, means for rotatively displacing said type-wheel, and means for pressing the record-sheet into printing relation with respect to the type on the type-wheel.

17. A pocket recording device for expense or other accounts, including a casing, a printing-wheel journaled for rotative movement within said casing and carrying type characters, a stem for said casing, a sleeve journaled in said stem, a gear mounted on said sleeve, gearing intermediate said gear and said type-wheel for rotatively actuating the latter, a support for a record-sheet a printing-platen independent of said support, and means for actuating said platen to press the record-sheet into printing contact with the type characters.

18. A pocket recording device for expense or other accounts, including a casing having a stem, a sleeve journaled to rotate in said stem, a rod extending through said sleeve for rotative and longitudinal movement therein, a disk carried by said rod, a gear carried by said sleeve, a printing-wheel, gearing actuated by the gear on said sleeve for rotatively actuating said printing-wheel, a record-sheet

support, means arranged to be engaged by
said disk when said rod is longitudinally
moved for rotatively displacing said record-
sheet support, and a cam carried by said disk
5 and a printing-platen arranged to be actuated
by said cam.

In witness whereof I have hereunto set my

hand, this 17th day of September, 1904, in the
presence of the subscribing witnesses.

ADOLPH G. CARLSON.
